UNITED STATES PATENT OFFICE.

WILLIAM PEARSALL, OF WORCESTER, MASSACHUSETTS, ASSIGNOR TO MATTHEW J. WHITTALL, OF WORCESTER, MASSACHUSETTS.

JACQUARD MECHANISM FOR LOOMS.

976,909.

Specification of Letters Patent. Patented Nov. 29, 1910.

Application filed March 21, 1904. Serial No. 199,109.

To all whom it may concern:

Be it known that I, WILLIAM PEARSALL, a subject of the King of England, residing at Worcester, in the county of Worcester and State of Massachusetts, have invented a new and useful Jacquard Mechanism for Looms, of which the following is a specification.

This invention relates to the selecting mechanism or jacquard for a loom.

One object sought to be accomplished by this invention is to provide a strong, simple, efficient and durable selecting mechanism which may be controlled by cards or strips of perforated material.

A further and special object of this invention is to provide means for automatically controlling the motion of the perforated material so that the jacquard mechanism may be made to repeat or reverse a pattern or section of a pattern as many times, or in such order, as desired to produce a complete design, such for example, as employed in rugs or other fabrics. In addition to this when one piece has been completed upon a loom employing a jacquard mechanism automatically controlled according to this invention, the parts will be left in position so that they will not require resetting or repositioning before commencing the weaving of a succeeding piece of the same design.

In the accompanying five sheets of drawings, Figure 1 is a side view partly broken away of a jacquard mechanism, and means for operating the same according to this invention. Fig. 2 is a diagrammatic view of one of the sets of coöperating parts which are employed in duplicate in a jacquard mechanism constructed according to this invention. Fig. 3 is a detail view of a set of operating connections to be hereinafter referred to. Fig. 4 is an enlarged view of the connections for shifting the controlling paper or other perforated material. Fig. 5 is a fragmentary front view thereof. Fig. 6 is a detail view of the levers operated by the chain. Fig. 7 is a detail view of a piece of controlling chain. Fig. 8 is a perspective view of one of the rolls or spools upon which the perforated paper is wound, also showing a piece of the perforated paper with the perforations therein numbered to indicate the sequence of picks of a repeating part of a pattern. Fig. 9 is an enlarged fragmen-

tary view of a piece of the perforated paper. Fig. 10 is a detail view showing the jacquard connections for shifting the chain. Fig. 11 is a diagrammatic view showing the character of a pattern which may be automatically woven on a loom employing the jacquard constructed according to this invention, and Fig. 12 is a detail view showing the construction of chain which would be employed for controlling the jacquard mechanism to weave a pattern of the character illustrated in Fig. 11.

In weaving rugs or fabrics of similar design upon the ordinary jacquard looms, a large percentage of the total time and labor is used up in positioning, repositioning, stripping and replacing the jacquard cards or other perforated controlling material.

The especial object of the present invention is to provide a repeating jacquard mechanism which is automatically controlled to weave rugs or fabrics of similar design without requiring any adjustment or manipulation of the jacquard by the user, and to control the parts so that upon the completion of one rug or other fabric the jacquard will be ready to commence weaving a second rug or fabric of the same pattern.

The amount of labor and the loss of time involved in shifting and manipulating the perforated cards of an ordinary jacquard mechanism can best be understood by an explanation of the manipulations required in weaving a rug of an ordinary typical design. For example, in weaving a rug designed with a border and a body portion comprising three repeats or duplicated pattern sections, the jacquard cards or other perforated material must be repositioned by a loom fixer or other skilled weaver at least six times.

Starting with the loom stripped, it is first necessary to set into position the set of cards or other perforated material which will weave a border section at one end of the rug. When this has been completed the loom must be stopped, the border jacquard cards removed, and the cards or perforated material for weaving one repeat of the pattern must be put in place. When the first repeat of the pattern has been woven, the cards or other perforated material must be wound back or repositioned to weave the second repeat, and this must also be done before commencing the third repeat, which, in

the design chosen, completes the body of the rug. After the body of the rug has been woven, that set of jacquard cards or other perforated material must be removed from the loom, and the cards or other material for weaving the border must again be put in place to weave the border which completes the other end of the rug.

The jacquard cards or other perforated material employed are necessarily delicate and easily injured, and such cards can be handled only with extreme care and by skilled workmen. For example, in stripping a loom or removing a set of jacquard cards of that class which use separate flat pieces of card-board, it is customary to wrap each card separately in tissue paper, or to interpose sheets of tissue paper between successive cards to prevent injury thereto. In spite of such precautions the perforated materials used for controlling jacquard mechanisms of looms are frequently torn and injured, and have to be replaced and repaired from time to time.

To provide a jacquard mechanism which will not require a hand manipulation of the perforated paper or other material which controls the same, I provide means for automatically shifting the paper in either direction with step by step feeds which will operate to automatically advance or rewind the paper either one step or two steps at a time as desired, and instead of employing successive rows of perforations for weaving successive picks of certain parts of a design (for example, a repeating part thereof) I employ alternate rows of perforations to weave one-half of a pattern section or repeat when the paper is advancing with a two-step motion in one direction, and I employ the intermeshed or remaining lines of perforations for weaving the second half of the repeat or pattern section when the paper is being rewound or moved back with a two-step motion in the opposite direction.

It results from feeding the paper or other controlling material either forward or backward, and with either a one-step or two-step progressive motion, that I am enabled to repeat any pattern sections as often as desired, and to weave on the border sections at the ends of the rugs or other fabrics without resetting or manipulating the perforated paper by hand. This will hereinafter be more fully explained by a specific description of the operation in weaving a rug of one particular characteristic design.

The devices which constitute the jacquard mechanism itself have been especially designed to provide a construction of sufficient strength to insure the accurate selection of comparatively heavy parts.

A jacquard mechanism constructed according to this invention has been employed in practice as the selecting device of the

loom for weaving tufted fabrics which is shown, described and claimed in my prior application for patent, filed Feb. 23, 1904, Serial No. 194,707, but it is of course capable of general application.

Referring to the drawings and in detail, S in Fig. 1, designates the ordinary shelf or support. Mounted on the shelf or support S are the side frames F which carry the moving parts of a jacquard mechanism 75 constructed according to this invention.

The parts which coöperate to form one of the sets of selecting instrumentalities are most clearly illustrated in Fig. 2. As shown in this figure, 15 designates a paper winding shaft having sprocket wheels 16 for engaging registering perforations in the strip of paper or other perforated material P. By means of the winding shaft 15 the paper is moved back and forth over a shield B 85 which is provided with a depression or groove for receiving the ends of the jacquard needles 17. Each of the jacquard needles 17 is provided at its upper end with a hook for engaging the rod 18 mounted in 90 the vertically movable frame 19. At an intermediate point each of the jacquard needles 17 is provided with an eye for receiving a pusher 20. At one end, the pushers or rods 20 extend through a guide-plate 95 21, and at their opposite ends, the pushers 20 coöperate with ledges or shoulders of a transversely movable pushing plate 71. Co-operating with the pushers 20 and arranged in alinement therewith are spring-pressed 100 rods 23 mounted in guide-plates 24 and 25. Vertically movable at the rear of the guide-plate 25 are harness slides 26. Each of the harness slides 26 is provided with movable pegs or pins 27 which are pushed out by the 105 spring-pressed rods 23, and which are held in adjusted positions by sheet metal friction springs 28. The pegs or pins 27 are returned to normal position by a laterally movable plate or board 29, and coöoperating 110 with the pins or pegs 27 which stand in their protruding or selected position is a lifting ledge or board 30. Connected to all but one of the vertically movable harness slides 26 are lingoies or strings 31 which are connected 115 at their lower ends to vertically movable rack-bars 32 containing the ends of the yarns or worsteds W, and which may present such worsteds or yarns for use in a tufting loom, for example, as described in my previous application for patent before referred to. One of the vertically movable harness-slides 26 instead of controlling threads or worsteds is connected to operate a pawl which shifts a chain which regulates the direction and 125 length of the intermittent advance movement of the perforated paper or other controlling material as hereinafter described.

In the operation of a set of selecting devices of a jacquard as thus constructed, the 130

jacquard needle 17 is first lifted, the controlling paper or other perforated material is shifted, the jacquard needle is allowed to descend, and if it finds a perforation of the paper, it will assume the position shown by full lines in Fig. 2, while if it rests upon or is supported by an unperforated section of paper, the pusher 20 of said needle will occupy the position shown by dotted lines. 5 The pushers are then shifted by the laterally movable plate 71, and through the spring-pressed rods 23 push out the selected pins or pegs 27 which are engaged by the vertically movable ledge 30 to raise the desired harness-frames 26. When the harness frames again descend to normal position, the plate 29 moves laterally and pushes back the pins or pegs 27.

The connections for operating the moving parts are most clearly illustrated in Fig. 1. As shown in this figure, 33 designates a rock-shaft which is journaled in the side-frames F and may be operated from the main cam-shaft of the loom. Extending 25 from the rock shaft 33 are arms 34 which are connected to vertical rods 35 carrying the lifting ledge 30. Journaled in hangers below the shelf or support S are cam-shafts 36, 37 and 38 which make one turn for each operation of the jacquard. Secured on the cam 36 is a cam which operates a lever 39 connected by a link 40 to a lever 41. At its opposite end, the lever 41 is slotted to engage a pin projecting from a vertically movable slide 42 which carries the 30 paper winding pawls, as hereinafter described. Mounted on the cam-shaft 37 is a cam which operates a lever 62 connected by a link 43 to a bell-crank lever 44. One arm 40 of the bell-crank lever 44 is slotted to receive a pin operating the peg returning plate 29. Mounted on the cam-shaft 38 is a cam operating a lever 45 which is connected by a link 46 to an arm 47 extending from a rock-shaft 48. Also extending from the rock-shaft 48 are arms 49 which are slotted at 45 their ends to engage pins operating the vertically movable slides 50.

The connections controlled by the vertically movable slides 50 at the opposite sides of the loom are most clearly illustrated in Fig. 3. As shown in this figure, each of the vertically movable slides 50 is provided with an inclined operating section 51 engaging 55 rollers to operate the horizontally movable slides 52 which carry the pusher-plate 71. Each of the slides 52 is provided with a rod 53 having an inclined operating section 54 engaging rollers to impart vertical movement to the needle lifting frame 19.

The paper winding pawls by means of which the paper may be advanced either one-step or two-steps at a time in either direction are most clearly illustrated in Figs. 4 65 and 5. As shown in these figures, the pawl

slide 42 is provided with two sets of oppositely facing pawls. The longer pawls 73 and 74 coöperate with a ratchet-wheel 96 on the winding shaft 15 to impart two-step movements to the paper, and the shorter 70 pawls 75 and 76 coöperate with the ratchet-wheel 96 to impart single-step movements to the winding shaft 15. The two sets of pawls 73 and 74; and 75 and 76, are connected by springs so as to normally be drawn into engagement with the ratchet-wheel 96. When required the pawls are rendered inoperative by being held out of engagement with their ratchet-wheel by means of guide-rollers. Two sets of such pawl-guiding rollers are 80 employed, one set being mounted upon a lever 78 connected by a link 80 to a lever 81, and the other set of rolls being carried by a lever 79 connected by a link 82 to a second lever 83. The levers 81 and 83 are mounted 85 side by side, and coöperate with a controlling chain which may be of the character employed in ordinary loom constructions. For example, as shown in Fig. 7, the chain may be built up by cross-pins and links, and 90 journaled on the cross-pins are two sets of operating rolls. Three different kinds of operating rolls are used; risers 90, or rolls of the largest diameter; idlers 91, or rolls of an intermediate diameter; and sinkers 92, or 95 rolls of the smallest diameter. The set of rolls nearest the front control the longer or two-step pawls 73 and 74, while the other set of rolls control the shorter or single-step pawls 75 and 76.

The path of the paper is most clearly illustrated in Fig. 1. As shown in this figure, the paper P may be wound from a roll or spool R between the guide rolls 55 and 56, and over the drum on the winding shaft 15 100 down between the winding rolls 58 and 59 to a receiving drum or spool T. The guide rolls 55, 56, 58 and 59 may be turned in unison with the winding shaft 15 by any desired connections, for example, by a chain 105 C, illustrated in Fig. 5. Mounted on the winding shaft 15 is a holding ratchet wheel which coöperates with a roll 77 carried by a spring-pressed lever to hold the paper in accurate position as shown in Fig. 4.

Considering now the position which will be occupied by the pawls as determined by the chain, when the levers 81 and 83 shown in Fig. 6, are controlled by a riser and idler on the chain respectively, the pawls will be positioned to advance the paper with a two-step movement at each operation; when the levers 81 and 83 are controlled by an idler and riser respectively on the chain, the pawls will be positioned to advance the 110 paper with a one-step movement at each operation; when the levers 81 and 83 are controlled by a sinker and idler respectively on the chain, the pawls will be positioned to impart a two-step reverse motion to the 115 120 125 paper.

paper at each operation; and when the levers 81 and 83 are controlled by an idler and sinker respectively on the chain, the pawls will be positioned to impart a single-step reverse motion to the paper at each operation of the loom. The chain is mounted upon drums carried by a winding shaft 93.

The connections for turning the shaft 93 are most clearly illustrated in Fig. 10. As shown in this figure, 94 designates a vertically movable piece which is controlled from one set of jacquard connections. Mounted on the piece 94 is a pawl 95 engaging the ratchet-wheel 96 on the shaft 93. Coöoperating with the ratchet-wheel 96 is a spring-pressed holding roller 97 for holding the chain in its adjusted positions.

As shown most clearly in Fig. 9, the row of perforations *p* for the jacquard connections controlling the winding of the chain are preferably located at the edge or margin of the paper, and by means of the constructions described each of these perforations advances the chain one link or step.

The character of the paper or other perforated material preferably employed is most clearly illustrated in Fig. 8. As shown in this figure, two strips of paper are preferably used, and these strips of paper are reinforced by ribbons or longitudinal bands which are perforated to engage the registering wheels. Instead of employing two separate strips, a single wide strip may be used, but I prefer to employ two separate strips in order to avoid the use of unusually wide paper. In cutting or perforating the paper to weave a repeat or pattern section which appears more than once on the completed fabric, the successive picks are controlled by every alternate row of perforations. For example, if one repeat of a pattern requires one hundred picks in weaving the same, the perforations of the paper may be of the character illustrated in Fig. 8. That is to say, while the paper is being advanced, the first fifty picks or the first half of the repeat would be controlled by every alternate line of perforations numbered from one to fifty; and during the weaving of the last fifty picks or the last half of the repeat, the picks would be controlled by alternate lines of perforations numbered from fifty to one hundred while the paper was being wound in the opposite direction. By using alternate lines of perforations to control successive picks of a pattern, and by winding the paper in reverse directions, the paper will be rewound to its starting point upon the completion of a repeat. The pattern chain provides automatic control for the winding of the paper to produce either the single step or two step advance or reverse winding of the paper required in weaving any of the ordinary rug patterns. This can best be comprehended by a consideration of the

operations which take place in weaving an ordinary rug design, such for example, as illustrated in Fig. 11.

The design of the rug shown in Fig. 11 consists of a border section at each end of the rug, and of a pattern which is repeated three times to form the body of the rug. To weave such a rug with a jacquard mechanism constructed according to this invention requires a chain of thirteen links. While the paper winding pawls are controlled by the first set of rolls *a* of the chain illustrated in Fig. 12, the paper will be advanced with a single step movement during the weaving of a border section *a*; while the pawls are controlled by the second set of rolls *b*, the paper will be advanced with a two-step motion during the weaving of a section *b*, or the first half of the first repeat; while the pawls are controlled by the third set of rolls *c*, a single pick will be woven; while the pawls are controlled by the fourth set of rolls *d*, the paper will be moved back in the reverse direction with a two-step motion, and the second half *d* of the first repeat or pattern will be woven; while the pawls are controlled by the fifth set of rolls *e*, a single pick *e* will be woven, completing the first repeat; while the pawls are controlled by the sixth set of rolls *f*, the first half *f* of the second repeat will be woven; while the pawls are controlled by the seventh set of rolls *g*, a single pick *g* will be woven; while the pawls are controlled by the eighth set or rolls *h*, the second half *h* of the second repeat will be woven; while the pawls are controlled by the ninth set of rolls *i*, a single pick will be woven, completing the second repeat; while the pawls are controlled by the tenth set of rolls *j*, the first half *j* of the third repeat will be woven; while the pawls are controlled by the eleventh set of rolls *k*, a single pick *k* will be woven; while the pawls are controlled by the twelfth set of rolls *l*, the last half *l* of the third repeat will be woven; and finally while the pawls are controlled by the thirteenth set of rolls *m*, the border section *m* of the rug will be woven.

The controlling chain preferably passes around its drum in the form of an endless loop, and upon the completion of a rug, it will be seen that the chain has completed its circuit, and inasmuch as the paper has been wound back into its original position, the parts are ready to automatically commence the weaving of a second rug or piece of fabric of the same design.

It is to be understood that one particular design has been chosen simply for illustration, and that a jacquard mechanism constructed according to this invention can be controlled to weave any design whatever, and at the completion of such design be positioned to automatically repeat the operation.

I am aware that many changes may be

made in practicing this invention by those who are skilled in the art, that ordinary loom mechanics may use a considerable variety of instrumentalities for the automatic control 5 of jacquard mechanisms, and that such automatic controlling devices can be used in connection with jacquard devices of different types from that which has been herein shown and described without departing from the 10 scope of this invention as expressed in the claims. I do not wish, therefore, to be limited to the construction herein illustrated, but

What I do claim and desire to secure by Letters Patent of the United States is:—

- 15 1. In a loom, the combination with weaving mechanism, of a continuous pattern surface having a border pattern section provided with perforations, and a double pattern section or repeat having perforations in 20 alternating rows, the perforations of one set of rows representing half of a figure, and those of the alternate set, taken in reverse order, representing the other half, whereby the pattern surface may be fed 25 forward by a single step motion along the border pattern section to weave the border, then fed continuously forward, but with a two-step motion, to weave the first single pattern section, then fed back with a two- 30 step motion to complete the double pattern section, whereby the pattern surface will then be in position to repeat the double pattern section or to weave the other border, without resetting the pattern surface.
- 35 2. In a loom, the combination with weaving mechanism, of a continuous pattern surface having a border pattern section provided with perforations, and a double pattern section or repeat having perforations in 40 alternating rows, the perforations of one set of rows representing half of a figure, and those of the alternate set, taken in reverse order, representing the other half, and means for feeding the pattern surface forward by a single-step motion, to weave one border, continuing the forward feed by a two-step motion over said double pattern section, automatically reversing the same and feeding back by a two-step motion 45 over the double pattern section, but on the alternate rows of perforations, automatically repeating both two-step motions the required number of times, whereby the pattern surface will be left at a point from 50 which either the double pattern section or border may be woven without resetting and then feeding the pattern surface back over the border pattern section to weave the second border.
- 55 3. In a loom, the combination with weaving mechanism, of a continuous pattern surface having a border pattern section provided with perforations, and a double pattern section or repeat having perforations 60 in alternating rows, the perforations of one

set of rows representing half of a figure, and those of the alternate set, taken in reverse order, representing the other half, and means for feeding the pattern surface forward by a single-step motion, to weave 70 one border, continuing the forward feed by a two-step motion over said double pattern section, moving the pattern surface one step to change from one row of perforations to the next one and weave one pick, automatically reversing the same and feeding back by a two-step motion over the double pattern section but on the alternate rows of perforations, automatically repeating both two-step motions the required number of times, 75 whereby the pattern surface will be left at a point from which either the double pattern section or border may be woven without resetting, and then feeding the pattern surface back over the border pattern section to 80 weave the second border.

4. In a repeating jacquard mechanism for looms, the combination of a perforated pattern surface having alternate lines of perforations for controlling successive picks, 90 and feeding devices for automatically imparting thereto a complete forward double space feed for a design or part of a design, automatically reversing, and then feeding a double space reverse feed during which the 95 successive picks are controlled by the lines of perforations of the controlling material alternating with those controlling the picks on the forward feed, whereby the parts will automatically be restored to first position 100 upon the completion of a design or part of a design.

5. In a jacquard mechanism for looms, the combination of a pattern surface, a ratchet-wheel, a vertically movable slide, means 105 operable by said slide for engaging the ratchet wheel to turn it in two directions and at a plurality of different speeds, and means for shifting said means operable by the slide to produce different feeds in either 110 direction.

6. In a jacquard mechanism for looms, the combination of a pattern surface, a ratchet-wheel, a movable slide, a plurality of pawls mounted on said slide for engaging each 115 side of the ratchet-wheel, and means for shifting the positions of said pawls to produce different feeds in either direction.

7. In a jacquard mechanism for looms, the combination of a pattern surface, a winding shaft therefor, a ratchet wheel on the winding shaft, a vertically movable slide, two sets each containing a plurality of pawls mounted on said slide to engage opposite sides of the ratchet wheel, and means for 120 shifting the positions of the pawls to produce different feeds in either direction.

8. In a jacquard mechanism for looms, the combination of a pattern surface, a ratchet wheel, two sets of pawls for engaging oppo- 130

site sides of the ratchet wheel, and means comprising guide rolls for said pawls for adjusting said pawls to produce different feeds.

5 9. In a jacquard mechanism for looms, the combination of a pattern surface, a ratchet wheel, two sets of pawls for engaging opposite sides of the ratchet wheel to feed said material, guide rolls, means for automatically shifting the guide rolls for adjusting said pawls to produce different feeds, and means for advancing said shifting means.

10 10. In a jacquard mechanism for looms, the combination of a pattern surface, a 15 ratchet wheel, two sets of pawls engaging opposite sides of the ratchet wheel to feed the pattern surface, guide rolls, a pattern chain for automatically shifting the guide rolls for adjusting said pawls to produce 20 different feeds, and means for automatically advancing the pattern chain.

11. In a jacquard mechanism for looms, the combination of a pattern surface, a winding shaft therefor, a ratchet wheel on the 25 winding shaft, a vertically movable slide, two sets of pawls mounted on the slide to engage opposite sides of the ratchet wheel, two rocking levers having guide rolls for adjusting the pawls to produce different 30 feeds, and a pattern chain having two sets of chain wheels for shifting the operating levers, and means for automatically advancing the chain.

12. In a jacquard mechanism for looms, 35 the combination of a pattern surface, a ratchet-wheel, a vertically movable slide, two sets of pawls mounted on the slide to engage opposite sides of the ratchet wheel, rocking levers having guide rolls for adjusting the pawls to produce different feeds, means for shifting the operating levers, and means for advancing the shifting means.

13. In a jacquard mechanism for looms, the combination of a pattern surface, a 45 ratchet wheel, a movable slide, pawls mounted on the slide for operating the ratchet wheel in opposite directions, means for adjusting the pawls to produce a plurality of different feeds in the same direction, a pattern chain having two sets of chain wheels for shifting said adjusting means, and means for advancing said chain.

14. In a jacquard mechanism for looms, the combination of a pattern surface having 55 marginal perforations, a winding shaft, a ratchet wheel on the shaft, two sets of pawls coöperating with the ratchet wheel, one set of pawls for shifting the sheet either forward or backward with a double spaced feed, and the other set of pawls for shifting the sheet forward or backward with a single spaced feed, means for adjusting the positions of said pawls, and jacquard connections controlled by the marginal perfora-

tions in the sheet for advancing said adjust- 65 ing means.

15. In a jacquard mechanism for looms, the combination of a pattern surface having marginal perforations, feeding devices therefor, means for adjusting the feeding devices 70 to produce different feeds, and a set of jacquard connections controlled by said marginal perforations for advancing the adjusting means.

16. In a jacquard mechanism for looms, 75 the combination of a pattern surface, feeding devices therefor, a pattern chain connected to adjust the feeding devices to produce different feeds, and a set of jacquard connections controlled by marginal perforations in 80 said pattern surface for advancing the pattern chain.

17. In a jacquard mechanism for looms, the combination of a pattern surface consisting of a strip of perforated paper, reels 85 or spools for said strip of perforated paper, a winding shaft, a ratchet wheel secured upon the winding shaft, two sets of pawls coöperating with the ratchet wheel, one set of pawls for shifting the perforated paper 90 either forward or backward with a double spaced feed, the other set of pawls for shifting the paper forward or backward with a single spaced feed, a pattern chain connected to adjust the positions of said pawls, and 95 a set of jacquard connections controlled by marginal perforations in the paper for advancing the pattern chain.

18. In a jacquard mechanism for looms, the combination with a pattern surface, of 100 a plurality of sets of jacquard connections, one of said sets of jacquard connections controlling the feed of the pattern surface while the rest of said sets of connections control the positions of yarns or threads in a loom. 105

19. In a jacquard mechanism for looms, the combination of a pattern surface, feeding devices therefor, and vertically movable jacquard harness-frames, one of which is connected to control the feed of the pattern 110 surface, while the remainder are connected to control the position of threads in a loom.

20. In a jacquard mechanism for looms, the combination of the strip of perforated paper, the paper shield for supporting the 115 paper, winding devices for feeding the paper, jacquard needles, each consisting of a wire hooked on to a vertically movable support at its upper end and having an eye at an intermediate point, a pusher movable 120 transversely through the eye of each jacquard needle, a pushing plate having ledges or flanges for shifting the pushers, vertically movable slides having pegs or pins to be pushed out by the operation of said 125 pushers, one of said slides being connected to control the paper feeding devices while the remainder of the slides are connected

to control the position of threads in a loom, a lifting bar for raising the selected slides, and a restoring plate for restoring the pins or pegs of the slides to normal position.

5 21. In a jacquard mechanism for looms, the combination of a pattern surface, winding devices for feeding said pattern surface, jacquard needles, and a set of slides, one of said slides having connections for controlling the feeding devices, the remainder of 10 the slides having connections for controlling the position of threads in the loom.

22. In a jacquard mechanism for looms, the combination of a pattern surface, a 15 ratchet wheel, two sets of pawls adapted to

be moved into position to coöperate with the ratchet wheel, one set for shifting the pattern surface either forward or backward for a double spaced feed and the other set for shifting the pattern surface either forward or backward for a single spaced feed, and jacquard connections controlled by the pattern surface for moving the pawls.

In testimony whereof I have hereunto set my hand, in the presence of two subscribing 20 witnesses.

WILLIAM PEARSALL.
